United States Patent Office

Des. 229,561

Patented Dec. 11, 1973

229,561

COMBINATION FLUSH VALVE AND CONTROL VALVE

James A. Sloan, River Forest, and Axel B. Nelson, Mount
Prospect, Ill., assignors to Sloan Valve Company

Filed Mar. 8, 1971, Ser. No. 122,257

Term of patent 14 years

The portion of the term of the patent subsequent to
July 14, 1984, has been disclaimed

Int. Cl. D23—01

U.S. Cl. D23—38

FIG. 2

FIG. 1

FIG. 3

FIG. 4

FIG. 1 is a front elevational view of a combination flush valve and control valve embodying our new design;

FIG. 2 is a top plan view thereof;

FIG. 3 is an elevational view taken from the left side thereof; and

FIG. 4 is an elevational view taken from the right side thereof.

We claim:

The ornamental design for a combination flush valve and control valve, as shown.
